UNITED STATES PATENT OFFICE.

VICTOR ERNEST GUILHEM, OF BORDEAUX, FRANCE.

DESIGN FOR A PICKLE JAR.

Application filed July 21, 1924. Serial No. 10,211. Term of patent 14 years.

To all whom it may concern:

Be it known that I, VICTOR ERNEST GUILHEM, French citizen, residing at Bordeaux, Gironde, France, have invented a new, original, and ornamental Design for Pickle Jar, of which the following is a specification, reference being had to the accompanying drawing, forming part thereof.

I claim:

The ornamental design for a pickle jar, as shown.

VICTOR ERNEST GUILHEM.
